Safety 1st Cabinet Lock, publicly disclosed prior to Sep. 10, 2014.

Primary Examiner — Prabhakar Deshmukh

(74) *Attorney, Agent, or Firm* — Wolf, Greenfield & Sacks, P.C.

(57) **CLAIM**

The ornamental design for a sliding cabinet lock, as shown and described.

DESCRIPTION

FIG. 1 is a front, left side and top perspective view of a sliding cabinet lock showing my new design;

FIG. 2 is a front, right side and top perspective view thereof;

FIG. 3 is a right side elevation view thereof;

FIG. 4 is a left side elevation view thereof;

FIG. 5 is a rear, left side and top perspective view thereof;

FIG. 6 is a rear, right side and top perspective view thereof;

FIG. 7 is a rear, left side and bottom perspective view thereof;

FIG. 8 is a rear, right side and bottom perspective view thereof;

FIG. 9 is a front, right side and bottom perspective view thereof;

FIG. 10 a front, left side and bottom perspective view thereof;

FIG. 11 is a top plan view thereof; and,

FIG. 12 is a bottom plan view thereof.

The broken lines show portions of the sliding cabinet lock that form no part of the claimed design.

1 Claim, 12 Drawing Sheets
